UNITED STATES PATENT OFFICE

158,307

EATING INSTRUMENT

Alois Molitor, Buffalo, N. Y.

Application June 23, 1948, Serial No. 147,150

Term of patent 14 years

(Cl. D44—29)

To all whom it may concern:

Be it known that I, Alois Molitor, a citizen of the United States, residing at Buffalo, in the county of Erie and State of New York, have invented a new, original, and ornamental Design for Eating Instrument, of which the following is a specification, reference being had to the accompanying drawing, forming part thereof.

Fig. 1 is a top view of the eating instrument, showing my design.

Fig. 2 is a top view thereof as it appears when the two members of the instrument are slightly separated.

Fig. 3 is a bottom view thereof.

Fig. 4 is a side view thereof.

Fig. 5 is a transverse section, taken on line 5—5, Fig. 4.

Fig. 6 is a transverse section taken on line 6—6, Fig. 4.

I claim:

The ornamental design for an eating instrument, as shown.

ALOIS MOLITOR.
